US00D574938S

(12) **United States Design Patent**
Martin et al.

(10) **Patent No.:** **US D574,938 S**
(45) **Date of Patent:** **** Aug. 12, 2008**

(54) **HEAT EXCHANGER**

(75) Inventors: **David Martin**, Concord, NC (US);
Gang Li, Manitowoc, WI (US); **David L. Schardt**, Franklin, TN (US)

(73) Assignee: **Hayward Industries, Inc.**, Elizabeth, NJ (US)

(**) Term: **14 Years**

(21) Appl. No.: **29/286,192**

(22) Filed: **Apr. 26, 2007**

(51) **LOC (8) Cl.** **23-03**

(52) **U.S. Cl.** **D23/323**

(58) **Field of Classification Search** **D23/314, D23/317, 332, 342, 333, 334, 335, 337, 351, D23/355, 378, 370, 387, 364, 336, 341, 383; 237/56, 67, 61, 62; 416/244 R, 247 R, 53.1, 416/53.2, 53.3; 392/365, 367, 347, 350, 392/373, 407, 433, 78 A; 165/154**

CLAIM

The ornamental design for a heat exchanger, as shown and described.

DESCRIPTION

FIG. 1 is a perspective view of a heat exchanger showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
